UNITED STATES PATENT OFFICE.

JAMES A. WIGGS, JR., OF BEAUMONT, TEXAS.

ROTARY DRILLING APPARATUS.

No. 862,954.

Specification of Letters Patent.

Patented Aug. 13, 1907.

Application filed April 10, 1906. Serial No. 310,943.

To all whom it may concern:

Be it known that JAMES A. WIGGS, Jr., a citizen of the United States, residing at Beaumont, in the county of Jefferson and State of Texas, has invented certain new and useful Improvements in Rotary Drilling Apparatus; and he does hereby declare the following to be a full, clear, and exact description of the invention, such as will enable others skilled in the art to which it appertains to make and use the same.

10 This invention relates to rotary drilling mechanism for boring wells and similar purposes and more especially to that kind or class of such mechanism wherein a rotary table or ring is employed, carrying gripping cones, jaws or rollers provided with means for closing the same on a tube, stem or rod so as to grip the latter and compel it to turn with the said ring. The chief object of the present invention is to provide improved means for permitting the vertical movement of the tube or rod and the gripping devices in the operation of 15 the machine, without removing the said devices from contact therewith.

The said invention consists in the mechanism hereinafter claimed for effecting this end and in certain other details of the machine for improving its general 20 efficiency and durability, all substantially as herein-after more particularly set forth.

In the accompanying drawings, Figure 1 represents a side elevation of a machine, partly in central vertical section, embodying my invention; Fig. 2 represents a 25 plan view of the same; Fig. 3 represents a side elevation of the machine, the driving shaft and frame being partly broken away; Fig. 4 represents a detail perspective view of one of the nuts 16; Fig. 5 represents a detail perspective view of one of the arms 9; Fig. 6 30 represents a detail perspective view of one of the brackets 14; Fig. 7 represents a detail view of one of the standards 7, in side elevation.

A designates the bed-frame of the machine and i the base plate fastened thereto by bolts a. Bearing 40 caps B B' hold the rotary driving shaft 24 on said plate and frame and are provided with bushings b, also with oil-cups d for lubricating the same. Said shaft is driven through sprocket wheel 23 or its equivalent, which is sleeved on said shaft and clutched at will by 45 a clutch collar 21 splined on said shaft, this clutch being operated by a shifting lever 22. The inner end of said shaft bears a table-driving bevel gear pinion 27, which meshes with a circular series of cog teeth 2^a on the under side of rotary table 2, supported on antifriction 50 rollers 4 in a race way 4^a; the latter being formed partly in said table and partly in said base plate. The said table has a downwardly extending cylindrical portion 2^b of reduced diameter to present a downward face in which the upper part of said raceway is formed; 55 and a further downward extension or stem 2^c, still her reduced in diameter, which fits into the central

opening of the baseplate and turns therein. Said table has a central circular opening 2^d from top to bottom. The tube or rod to be clamped and rotated extends in operation down through the said central opening or bore 60 of the table and of course through the base plate surrounding the same. The two pairs of gripping rollers 30 are loose on their shafts 15, which are mounted at their ends in the inner perforated ends of arms 9 and held thereto in any convenient way. The outer ends of said 65 arms are mounted freely on outer shafts 8, which are parallel to said shafts 15. These outer shafts 8 are held in arms 14^a of brackets 14 which inclose the nuts 16 of the said right and left screw-threaded adjusting shafts 6. Each nut is convex on its periphery and the bracket is 70 shaped internally to fit the same, thereby allowing for any slight imperfection of fit in the other parts. There is also a ratchet wheel 18, fast on the middle part of each screw-shaft, engaged by a pawl 19^a carried by a bifurcated lever 19, mounted thereon. Each lever 75 19 and the ratchet wheel which it straddles are located between the upwardly extending bifurcations of a support or standard 7, having a cap 3 bolted thereon, to complete the bearing for the middle part of that screw-shaft. The two standards 7 are in all respects 80 alike and support the entire gripping mechanism. Their stems 7^a are set into holes 5 constituting sockets flush with the top of the table, such sockets and stems being of sufficient depth to permit considerable upward play of the said stems and of the whole gripping 85 mechanism, allowing for the jumping of the drilling tool when it strikes some hard substance and for all vertical jar in running the machine. If the jumping should be so extreme as to displace the standards there will be nothing but the smooth table below the shafts 90 and their appurtenances, and little risk of injury; whereas if the bearing were open and the standards not vertically movable, the shafts 6 might spring considerably above the said standards and break the bifurcations of the latter in their descent. Also a slight upward movement would dislodge them.

The arms 9, inner shafts 15 and gripping rollers 30 are free to rock on shafts 8 without disturbing the latter; also to permit the independent vertical motion of the shafts 8 and standards 7 without loosening their 100 grip on the drill tube or drill rod. This independence of motion between the supporting standards and the gripping devices affords an additional protection against injury from jumping, since it permits a certain amount of upward motion without lifting the standards. It 105 also permits the tool-carrying tube or rod to be slightly raised by hand, when there is occasion to repair or sharpen the tool, without separating any parts or changing the grip.

In the periphery of the rotary table 2 is formed an 110 annular groove 2^b which receives the inwardly presented curved rib or flange 31^a of each of four supporting

and fastening legs or frames 31 as indicated by dotted lines in Fig. 2, arranged around the said table and secured by bolts 31^b passing through their bases, slots 31^a having been provided in said frames. The base of

- 5 each of said frames is guided and braced by a pair of guide walls or raised lugs 31^c on base plate *i*. The said frames while in operative position securely clamp the said table to the said base plate, while permitting rotary motion to said table. They also brace it against
10 strain incident to the action of the drilling tube or rod and are themselves braced against lateral or torsional strains by the walls or raised lugs 31^c.

Having thus described my invention, what I claim as new and desire to secure by Letters Patent is:

- 15 1. In a rotary drilling machine, a set of tube-gripping devices, in combination with a rotary table, provided with sockets, supports for said gripping devices set freely into said sockets and caps covering the tops of said supports to hold the said gripping devices in place substantially as set forth.
- 20 2. In a rotary drilling machine, a rotary table provided with sockets in combination with standards set into said sockets and bifurcated to afford shaft bearings, caps completing said bearings, screw shafts mounted in said bearings, means for rotating said screw-shafts, nuts engaging said screw-shafts and devices operated by said nuts and carrying the gripping rollers, all of the above mentioned mechanism being supported by the said standards substantially as set forth.
- 25 3. In rotary drilling mechanism, the combination of tube-gripping devices with adjusting screw shafts, means for supporting said shafts, nuts engaging said shafts and brackets inclosing these nuts and supporting said gripping devices, the said nuts being convex on their outer faces and the said brackets similarly shaped internally substantially as set forth.
- 30 4. In rotary drilling mechanism, the combination of tube-gripping rollers arranged in pairs and their shafts 15, with parallel shafts 8 and arms connecting the former shafts to the latter so as to allow the shafts 15 to rise and fall independently, brackets connected to shafts 8,

45 nuts inclosed by said brackets, screw-shafts engaging the said nuts, means for rotating said screw shafts to close or open the gripping devices, supports for said screw shafts and a rotary table carrying said supports substantially as set forth.

50 5. In rotary drilling mechanism, the combination of tube-gripping rollers arranged in pairs and their shafts 15, with parallel shafts 8 and arms connecting the former shafts to the latter so as to allow shafts 15 to rise and fall independently, brackets connected to shafts 8, nuts inclosed by said brackets, screw-shafts engaging said nuts, means for rotating said screw-shafts to close or open the said gripping devices, vertically movable standards, providing bearings for said screw-shafts, caps covering said 55 bearings and holding said shafts to said standards and a rotary table having sockets in which the stems of said standards are freely set, permitting them to rise independently substantially as set forth.

6. In rotary drilling and boring mechanism, a rotary 60 table having a smooth upper face and recesses in the same, in combination with tube gripping devices, rotary screw-threaded shafts operating the said gripping devices and supports affording bearings for said shafts, these supports being provided with stems which set freely into 65 said recesses, in order that the said supports, shafts and gripping devices may be at liberty to rise together in case of a sudden upward jar of the tube and that in falling they may have only the smooth surface of the table below them substantially as set forth.

7. In rotary drilling or boring mechanism, a rotary table having a smooth upper face and recesses in the same, in combination with tube gripping devices, means for operating the said gripping devices and supports for said means and devices, the said supports setting freely into 75 said recesses in order that said gripping devices, operating means and supports may all be free to rise together in case of a sudden upward jar of the said tube substantially as set forth.

In testimony whereof, I have signed my name to this 80 specification in the presence of two subscribing witnesses.

JAMES A. WIGGS, Jr.
